UNITED STATES PATENT OFFICE.

EDWARD SWEENEY, OF NORRISTOWN, AND GEORGE A. HUNSBURGER, OF POTTSTOWN, PENNSYLVANIA.

BOBBIN.

Application filed December 3, 1923, Serial No. 678,257. Renewed December 9, 1925.

To all whom it may concern:

Be it known that we, EDWARD SWEENEY and GEORGE A. HUNSBURGER, citizens of the United States, residing at Norristown and 5 Pottstown, respectively, in the county of Montgomery and State of Pennsylvania, have invented new and useful Improvements in Bobbins, of which the following is a specification.

10 This invention relates to bobbins, cones or similar structures used in weaving or knitting, and an object of the invention is to provide a covering for cone bobbins of the conventional type now in use, which will 15 eliminate the large majority of the disadvantages and inconveniences contingent with the use of the present type of bobbins and cover, among which are the catching of the thread, particularly in cases of thread, silk, 20 or artificial silk, upon rough places in the bobbin, causing rupturing of the thread or yarn, improper unwinding and what is commercially known as "bunching" of the 25 yarn resulting in loss of yarn and causing imperfections in the articles being made.

Another object of this invention is to provide a cover as specified which provides an outer roughened surface which is resilient and embodies sufficient roughness to permit 30 the proper winding of the yarn thereon or unwinding therefrom and which also embodies sufficient resiliency to permit yielding of minute portions of the roughened surface to prevent the catching or slipping 35 of the yarn thereon.

Other objects of the invention will appear in the following detail description, and in the accompanying drawings wherein:

Figure 1—is a view partly in side elevation and partly in section, showing one of the improved covers mounted upon a bottle bobbin.

Figure 2—is a view partly in side elevation and partly in section, showing one form 45 of the improved cover mounted upon a cone bobbin.

Figure 3—is a section, showing parts in elevation, of a modified form of the bobbin.

Figure 4—is a side elevation of a further 50 modified form of bobbin cover.

Referring more particularly to the drawings, the bottle bobbin 1 of approved type is illustrated in Figure 1 of the drawings, and it is understood, that in the usual 55 proved type of bottle bobbins in use the

substantially frustro-conical body 2 is made of wood and has its outer surface roughened to permit the proper winding of the yarn thereon. However, in practical use, it has been found that in unwinding, the yarn 60 catches on rough places in the outer surface of the bobbin body 2 and breaks, or causes "bunching" of the yarn on the bobbin, and consequently, results in loss of 65 yarn and imperfections in the article being made. To overcome such features, a covering 3 is made of soft rubber preferably of what is commonly known as sponge rubber, and the outer surface of the covering 3 is rough—as shown at 4—said roughness being provided by the irregularities in the rubber caused by the air holes and spongy construction of the rubber. The 70 roughened surface 4 embodies sufficient roughness to permit the proper winding of 75 the yarn or thread thereon. However, the resiliency of the rubber will permit yielding thereof and prevent the yarn from catching or hanging thereby permitting the use of all the yarn on the bobbin and eliminating 80 the waste usually caused at the finish of any individual bobbin, as well as eliminating 85 the disadvantages above enumerated.

In Figure 2 of the drawings, a cone bobbin 5 of approved type is illustrated which 85 cone bobbin is made of pasteboard, and in the present construction of such bobbins their outer surfaces are roughened and the action on the yarn is the same as above mentioned, relative to the body 2 of the 90 bottle bobbin and to overcome this, the covering 6 which is also made of spongy rubber is provided. In Figure 2 of the drawings, the cover 6 entirely encloses the bobbin 5, and in such cases, it is necessary that 95 the tip or apex portion 7 of the cover 6 have its outer surface smooth to permit the yarn to "run off" the bobbin, while the major portion of the outer cover 6 is roughened, as shown at 8, in the same manner as 100 the cover 3 is roughened.

In Figure 3 of the drawings, the modified form of the bobbin is shown in which the main conical body 10 is formed of hard rubber and the outer surface of the hard rubber 105 has a covering or layer 11 of spongy rubber thereon, which is vulcanized to the outer surface of the body 10 providing substantially a one-piece bobbin comprising the hard inner portion and the soft spongy re- 110

slient or pliable outer portion. The outer surface of the spongy or resilient portion 11 is roughened, as shown at 12, all over, with the exception of the outer surface of the 5 tip or apex portion 13 which is smooth to permit the yarn to run off the bobbin freely.

In Figure 4 of the drawings, a further modified form of the bobbin structure is shown in which the cover 20 which is made 10 of soft spongy rubber is shown as tacked, or otherwise suitably attached to the cone 21. In this form the covering 20 may be cut from a sheet of spongy rubber and either tacked, stitched or otherwise suitably attached 15 to the cone bobbin 21, and the covering 20 is shown shorter than the cone bobbin 21 leaving the tip or apex 22 of the bobbin free from the covering, so as to facilitate the running off of the yarn from the 20 bobbin.

It is to be understood, that in the construction of the moulded forms of covering, as shown in Figure 2 of the drawing, the apex of the bobbin proper, may be left free 25 from the covering, as shown in Figure 4 of the drawings, without departing from the spirit of this invention, and the same is also true of making the type of bobbin, as illustrated in Figure 3 of the drawings.

30 It is, of course, to be understood, that the invention may be constructed in various other manners and the parts associated in different relations, and therefore, we do not

desire to be limited in any manner, except as set forth in the claims hereunto appended. 35

What we claim is:

1. As a new article of manufacture, a cover for yarn bobbins formed of sponge rubber and having a rough outer surface.

2. As a new article of manufacture, a 40 cover for yarn bobbins formed of sponge rubber and having a rough outer surface, the outer surface of the apex portion of said covering being smooth.

3. As a new article of manufacture, a 45 bobbin comprising a body formed of a compound of hard rubber and having an outer covering of resilient sponge rubber mounted thereover.

4. As a new article of manufacture, a bobbin 50 comprising a body formed of a compound of hard rubber and having an outer covering of resilient sponge rubber mounted thereover, and vulcanized thereto.

5. As a new article of manufacture, a bobbin 55 comprising a body formed of a compound of hard rubber and having an outer covering of resilient sponge rubber mounted thereover and vulcanized thereto, the outer surface of said covering being rough, 60 the apex portion of the outer surface of said covering being smooth.

In testimony whereof we affix our signatures.

EDWARD SWEENEY.

GEORGE A. HUNSBERGER.
